ATTORNEY

UNITED STATES PATENT OFFICE

170,427

TOY TRAIN BLOCK PUZZLE

George Peterson, Los Angeles, Calif.

Application April 22, 1952, Serial No. 19,430

Term of patent 3½ years

(Cl. D34—15)

To all whom it may concern:

Be it known that I, George Peterson, a citizen of the United States, residing in the city and county of Los Angeles and State of California, have invented a new, original, and ornamental Design for a Toy Train Block Puzzle, of which the following is a specification, reference being had to the accompanying drawing, forming part thereof.

Fig. 1 is a side elevational view of a toy train block puzzle, showing my new design;

Fig. 2 is a front elevational view thereof;

Fig. 3 is a rear elevational view thereof;

Fig. 4 is a top plan view thereof; and

Fig. 5 is a bottom plan view thereof.

I claim:

The ornamental design for a toy train block puzzle, substantially as shown.

GEORGE PETERSON.
